UNITED STATES PATENT OFFICE

HORATIO G. CRESS, OF TROY, OHIO

DESIGN FOR A MEMORANDUM SLATE

Application filed November 14, 1928. Serial No. 28,876. Term of patent 3½ years.

To all whom it may concern:

Be it known that I, HORATIO G. CRESS, a citizen of the United States, residing at Troy, in the county of Miami and State of Ohio, have invented a new, original, and ornamental Design for a Memorandum Slate, of which the following is a specification, reference being had to the accompanying drawing forming a part thereof.

I claim:

The ornamental design for a memorandum slate, as shown.

HORATIO G. CRESS.
